ALEXANDER McLEAN NICOLSON, OF NEW YORK, N. Y., ASSIGNOR, BY MESNE ASSIGNMENTS, TO FEDERAL TELEGRAPH COMPANY, A CORPORATION OF CALIFORNIA

MULTIPLE RESONANT ACOUSTIC DEVICE

Application filed September 17, 1927. Serial No. 220,072.

This invention relates to acoustic devices, and more particularly to a device arranged to reproduce sound waves which may have one or a plurality of frequencies covering a relatively wide band of frequencies, as in the reproduction of speech, music, and other sounds transmitted by radio or carrier waves, or recorded on a record.

It is an object of this invention to provide a device of the class described, which shall reproduce the sound desired with a high degree of fidelity and with minimum distortion.

It is a further object of this invention to provide such a device which will not require the use of excessive power for high quality reproduction as is the case in most systems at present in use.

It is a further object of this invention to provide a device of the class described, which may be constructed and operated at minimum cost.

Still further objects and advantages of my invention will be apparent from the specification.

The features of novelty which I believe to be characteristic of my invention are set forth with particularity in the appended claims. My invention itself, however, both as to its fundamental principles and as to its particular embodiments will best be understood by reference to the specification and accompanying drawing, in which:

Figure 1 is a top plan view of one form of apparatus according to my invention.

Figure 2 is a front elevation thereof; and,

Figure 3 is a diagrammatic view of a modified form utilizing a different form of sound radiating element.

In accordance with my invention, I provide a multiplicity of sound generating elements, or acoustic amplifiers, which may be in the form of horns, cones, discs, or the like. The various sound generating elements are arranged to have different natural frequencies disposed over the range desired to be reproduced, and preferably a sufficient number of such devices will be provided so that for any sound frequency which it is desired to reproduce, at least one of said elements responds at a frequency in the neighborhood of its nat-

ural frequency. As a result, it will be understood that the resonance of each element comes into action in such manner that no matter which frequency is being reproduced, a considerable amplification of sound is obtained through the natural resonance of some one or more of the sound reproducing elements, thereby producing the maximum sound response for minimum power input, or conversely, permitting the usual volume of sound with a considerably less power input, thereby permitting the substitution of conventional amplifying tubes for so-called power tubes in audio frequency amplifiers without a substantial decrease in the volume or quality of sound output.

Preferably, a single means is utilized for energizing all of the sound generating elements, which means may take the form of the usual electromagnetic driver, or an electrostatic driver; however, for certain purposes, I prefer to use a piezo-electric crystal device of any suitable type well known in the art, such for example, as a crystal of Rochelle salt exhibiting the well known hour glass configuration, or, various improved forms thereof, such as described and claimed in my co-pending applications, entitled "Cast piezo-electric device", Serial Number 155,897, filed December 20, 1926; "Composite piezo-electric crystal device" Serial Number 155,898, filed December 20, 1926; "Composite piezo-electric torsion device" Serial Number 155,899, filed March 11, 1927; "Internally clamped composite piezo-electric torsion device", Serial Number 155,900, filed Dec. 20, 1926; "Method and apparatus for producing electric oscillations", Serial Number 155,901, filed Dec. 20, 1926; and, "Mechanical coupling for piezo-electric crystal device", Serial Number 160,360, filed Jan. 11, 1927.

In the preferred form of my invention, a single piezo-electric crystal device is utilized having a stress plate rigidly connected thereto and adapted to be vibrated by the crystal device when electrical oscillations are impressed thereon. The said stress plate is provided with mechanical terminals, each adapted to energize one of the sound generating elements. The sound generating elements,

themselves, may, for example, be in the form of cones, having different diameters, solid angles, and constructed of different material and having different weight. The stress plate, itself, may also be arranged so that its mass and elasticity are different in different sections corresponding to the sound reproducing element connected at any particular section.

10 Referring more particularly to Figures 1 and 2, 1 designates a piezo-electric crystal device such as a crystal of Rochelle salt exhibiting the well known hour glass configuration and having an exterior belt electrode 2, of 15 conducting material, such as a layer of metal foil or the like, and an internal electrode 3, passing through an opening formed within the crystal normal to the plane of the base thereof. The crystal 1 may be mounted upon 20 a suitable base plate 4 and a suitable stress plate 7 of elastic material such as steel, is rigidly secured to the top face thereof. The crystal 1, the base plate 4, and the stress plate 7 may be secured in any desired relation and 25 a compressive bias exerted upon the crystal by providing the electrode 3 in the form of a bolt having a head 5 engaging the base plate and provided with a suitable nut 6 at its opposite end, by means of which the desired 30 compression may be exerted upon the crystal.

If now, a difference of potential be impressed between the electrodes 2 and 3, the crystal itself will tend to deform in a manner such that the stress plate 7 will rotate slightly 35 with respect to the base plate 4, as is well known: and, if an alternating electromotive force be impressed, the deformation will be proportional in amplitude and frequency to the impressed electromotive force.

40 Connected to the stress plate 7, I provide a plurality of sound reproducing elements, such for example as cones 10, 11, 12, 13, 14, 15, 16 and 17, it being understood that the size, shape and material of the sound generating elements are so chosen that each of 45 these elements has a natural resonant frequency of response different from that of the other elements, and distributed over the range of frequencies which it is desired to 50 reproduce.

It is to be understood that the type, number and arrangement of the sound reproducing elements is not limited to those shown, since the arrangement is merely by way of 55 ample.

The cones are preferably fastened at their apexes to the stress plate 7 by means of suitable bolts 18 engaging tapped holes in the stress plate 7. Suitable filling blocks 19 may 60 be utilized to reinforce the apexes of the various cones and serve to hold the bolt heads. Suitable extensions 20, 24, 25, 26, 27, 28 and 29 may be provided on the stress plate 7, if desired, to which the sound generating elements may be directly attached, but these may

be omitted under certain conditions. It will be understood that by the proper proportioning and shape of said extensions, the resonant frequency of the corresponding sound generating elements may be modified or otherwise influenced. In addition, parts of the stress plate 7 may be cut away or otherwise removed, to form as many openings such as 21 as may be desired, or external sections may be removed as at 22 and 23 to form neck portions: also, the extensions may be given any suitable shape as 20, 28 and 29, all of the said modifications of the form of stress plate 7 serving to alter the natural frequency of response of the sound generating elements by alteration of the mass and elasticity of each individual sound generating element.

75 While I have shown cones 10, 11, 12, 13, 15 and 17 as straight side cones, and cones 14 and 16 as curved side cones, it will be understood that other forms of diaphragms may be used, or that horns may also be utilized which may have individual diaphragms adapted to be driven by stress plate 7: such an arrangement is shown in Figure 3, in 90 which the stress plate 7 is shown broken away adjacent one end for the purpose of simplicity. In this arrangement, 30, 31 and 32 represent horns of different length, cross section and degree of opening, having different natural frequencies. Each of the horns is provided with a diaphragm secured at its edge at the throat of the horn, preferably in the form of a relatively small cone having its apex pointing toward the bell of the horn. 100 In the arrangement shown, the horns are preferably made of suitable light material such as paper or the like, so as to be entirely supported and carried on the diaphragms 33, 34 and 35, whereby the horn itself as well as the air enclosed thereby, is subject to vibration.

105 As an alternative, a single diaphragm may be utilized feeding all of the horns which may all be connected to the sound box in 110 which the diaphragm operates: in such an arrangement, it will usually be preferable to construct the horns of heavier material and to make use only of the vibration of the air enclosed in the horns, the horns, themselves, not being directly vibrated except through the vibration of the air contained therein.

115 While I have shown and described my invention as a sound reproducer, it should be understood that it may be utilized also as a 120 microphone; that is to say, when sound waves are permitted to fall upon it, it will deliver an electromotive force proportional in frequency and amplitude to such sound waves.

125 While I have shown and described certain preferred embodiments of my invention, it will be understood that modifications and changes may be made without departing from the spirit and scope of my invention, as will be understood by those skilled in the art.

I claim:—

1. A sound reproducing device comprising a multiplicity of sound generating elements, each of said sound generating elements having a different natural frequency of response, said elements being so arranged that the response frequencies are distributed over the range of frequencies to be reproduced, a resilient plate adapted to be shaped to predetermine its acoustic characteristics, and a single means connected to said resilient plate for energizing all of said sound reproducing elements.

2. A sound reproducing device comprising a multiplicity of acoustic amplifying elements having different natural frequencies, said elements being so constructed that the natural frequencies of response are distributed over the band of frequencies desired to be reproduced by said device, a metallic plate, means for securing said elements to said plate, and a single means secured to said plate for energizing all of said amplifying elements.

3. A sound reproducing device comprising a multiplicity of acoustic amplifying elements having different natural frequencies, said elements being so constructed that the natural frequencies of response are distributed over the band of frequencies desired to be reproduced by said device, and a single means attached to said amplifying elements for energizing all of said amplifying elements, said means comprising a piezo-electric crystal.

Signed at New York city, in the county of New York and State of New York this 16th day of September, A. D. 1927.

ALEXANDER McLEAN NICOLSON.
